UNITED STATES PATENT OFFICE.

FRANCISCO DIAZ, OF WINSLOW, ARIZONA.

FILM DEVELOPER.

Application filed February 13, 1922. Serial No. 536,227.

To all whom it may concern:

Be it known that I, FRANCISCO DIAZ, a citizen of the United States, residing at Winslow, in the county of Navajo and State 5 of Arizona, have invented new and useful Improvements in Film Developers, of which the following is a specification.

This invention relates to photographic apparatus, particularly to devices for handling films in strip form, and has for its object the provision of a novel device for carrying out the developing, fixing, and washing of strips of film in a dark room, the invention having for one of its important 10 objects the provision of means whereby strips of any length may be handled, regardless of the size of the individual films and the number of exposures on the strip, ample adjustment being provided for taking 15 care of all variations.

Another object is the provision of a device of this character which needs no enclosing casing or tank inasmuch as it is designed for use in a dark room.

25 A further object is the provision of a device of this character which is so constructed and adjusted as to hold the film strip under the proper tension while the strip is being moved mechanically through the proper solution to exert the proper action upon the films.

Another object is the provision of a device of this character which may be readily disassembled for convenience in packing for storage or transportation, the device being 30 furthermore intended to be properly supported upon a table, shelf or equivalent support and therefore requiring no special base.

An additional object is the provision of a device of this character which will be simple 40 and inexpensive in construction, easy to use, highly efficient in action, durable in service, and a general improvement in the art.

With the above and other objects and advantages in view, the invention consists in the details of construction to be hereinafter more fully described and claimed and illustrated in the accompanying drawings in which—

Figure 1 is a front elevation of the complete device.

Figure 2 is a side elevation showing a film carried thereby.

Figure 3 is a rear elevation.

Figure 4 is a cross sectional view taken 55 through the upper spool.

Figure 5 is a cross sectional view taken through the upper end of the standard.

Figure 6 is a cross sectional view on the line 6—6 of Figure 1.

Figure 7 is a cross sectional view on the line 7—7 of Figure 1.

Figure 8 is a fragmentary sectional view of the standard and slidable sleeve, this view illustrating the adjusting feature.

Referring more particularly to the drawings, the letter A designates a table, shelf, or other support upon which my device is intended to be used. In carrying out my invention I provide a vertically disposed standard 10 which may be formed of two 65 strips of wood secured together with a small block interposed between the lower ends thereof or which may be formed simply as a single upright elongated support formed with a vertical slot 11 extending to its upper 70 end. At its lower end the standard 10 is provided with penetrating prongs 12 adapted to bitingly engage the top of the table or other support A. For bracing the standard and holding it rigid it is conceivable 75 that various expedients might be resorted to, though in actual practice I prefer to use a plurality, preferably three, of wires 13 which are secured to the upper end portion of the standard as by means of screw 80 eyes 14 and which are connected at their lower ends with other screw eyes 15 screwed into the table top. Secured upon opposite sides of the standard 10 at the upper end 85 thereof, are metal plates 16 and threaded 90 through one side of the standard is a thumb screw 17 which projects into the slot 11, for a purpose to be described.

Slidably associated with the standard 10 is a post 18 which is slidable along the slot 95 11 and which has lateral displacement in one direction prevented by the plates 16, and this post may be secured in any desired adjustment by means of the thumb screw 17. At its lower end the post 18 has secured 100 thereon metal plates 19 which bear against opposite sides of the standard, as clearly shown. It should also be stated that the rear side of this post 18 is formed as a rack bar or is provided with a series of ratchet 105 teeth 20.

Slidable vertically upon the post 18 is a metal sleeve 21 which has its rear side provided with ears 22 between which is pivoted 110 a spring-pressed pawl 23 engageable with

the ratchet teeth 20 for holding this sleeve at any adjusted position along the post. Suitably secured to and extending from the front side of the sleeve 21 is a spindle 24 upon which is rotatably mounted a flanged spool 25 having an eccentric handle 26 by means of which it may be rotated.

Slidable vertically within the lower portion of the slot 11 is a block 27 upon one side of which is secured a plate 28 which overlaps the standard at the sides of the slot therein and which carries a depending angularly shaped spindle 29 upon which is rotatable a flanged spool 30 disposed in vertical alignment with the spool 25. Pivoted at 31 upon the opposite side of the block 27, is an arm 32 adapted to be swung transversely with respect to the slot 11 to form a guide for the block and to prevent the latter from slipping out of the slot 11.

In the operation of my device, the film to be developed is unrolled and the ends thereof are cut at the margins of the black paper backing so that the film will be freed from the backing paper. Subsequently to this, the two ends of the film are brought together to form a band and are secured, for instance, as by pins. This band of film is then slipped onto the two spools 25 and 30 with the emulsified side outermost. The post 18 must of course, be adjusted along the slot 11 and the sleeve 21 must likewise be adjusted along the post so that the spools will be the required distance apart, depending upon the size of the film strip and the number of exposures thereon. Assuming that the parts have been properly positioned in this way, it is necessary that the operator press upon the spring-pressed pawl 23 and release the same so that the sleeve 21 may be moved upwardly, carrying with it the film, and also moving the block 27 upwardly, until the film has been elevated a sufficient distance to permit a suitable vessel or pan containing clear water only to be placed under the spool 30. The operator then lowers the film so that the lower spool 30, will be submerged in the water, after which the spool 25 is rotated by means of the handle 26, to bring all the film through the water for the purpose of softening the film. The film is then again elevated and the pan of water is replaced by a pan of developer solution, after which the film is again lowered, and the spool 15 rotated to make the film pass through the developing solution, the speed of course depending upon various conditions. After development has been thus effected, the pan of developer is moved and replaced by a second pan of clear water and the operation is repeated to effect the intermediate washing of the film, after which this pan of water is removed and replaced by a pan containing the fixing solution. The film is again lowered and the

spool 25 turned to bring all portions of the film under the influence of the fixing solution, after which the pan of fixing solution is removed and replaced by a third pan of plain water so that when the film is again lowered and the spool 25 turned the film will be washed.

From the foregoing description and a study of the drawings it will be apparent that I have thus provided a very simply constructed and consequently inexpensive device by means of which developing and fixing, together with the necessary washing of strips of film may be readily carried out in a very rapid and efficient manner and with the minimum degree of labor. It will also be observed that the various parts of the device may be taken apart so as to pack in a convenient package for transportation or storage. It will also be observed that owing to the simplicity of the construction there is nothing to get out of order and the device should therefore have an extremely long life.

While I have shown and described the preferred embodiment of my invention, it is of course to be understood that I reserve the right to make such changes in the form, construction and arrangement of parts as will not depart from the spirit of the invention or the scope of the subjoined claims.

What is claimed is:—

1. A device of the character described comprising an upstanding slotted support, a post slidable along said slot, a sleeve member vertically adjustably mounted upon said post and carrying a spindle, a spool rotatable on said spindle and having a handle, a block slidable along the lower end of said slot and carrying a spindle, and a flanged spool on said last named spindle.

2. A device of the character described comprising an upstanding support, a post slidably adjustably mounted upon said support, a spool carried by said post and having a handle, and a second spool rotatably mounted and adjustable vertically along the lower portion of the support below the first named spool.

3. A device of the character described comprising a support having its lower end provided with penetrating means adapted to engage a table or the like, guide wires connected with the support and adapted to be secured to the table in spaced relation to the lower end of the support, a spool rotatably mounted and vertically adjustably supported from the lower end of the support, and a second spool rotatably mounted and disposed for vertical adjustment upon the upper end of the support and arranged above the first named spool.

4. A device of the character described comprising an upstanding support, a post vertically slidably mounted upon said sup-

port and having its rear face formed with ratchet teeth, means for securing said base at a selected position, a sleeve slidable upon the post and carrying a releasable spring-
5 pressed pawl engaging the ratchet teeth, a spindle extending from the sleeve and carrying a rotatable sleeve having a handle, a block slidable with respect to the lower portion of the standard, a spindle carried by the block and supporting a rotatable spool 10 disposed in alignment with the first named spool.

In testimony whereof I affix my signature.
FRANCISCO DIAZ.
